UNITED STATES PATENT OFFICE.

JACOB H. SCHEUER, OF NEW YORK, N. Y.

DESIGN FOR A TOILET-BRUSH.

44,416.

Specification for Design.

Patented July 29, 1913.

Application filed May 14, 1913. Serial No. 767,707. Term of patent 14 years.

To all whom it may concern:

Be it known that I, JACOB H. SCHEUER, a citizen of the United States, residing in the city, county, and State of New York, have invented a new, original, and ornamental Design for Toilet-Brushes, of which the following is a specification, reference being had to the accompanying drawings, forming part hereof.

In the drawings: Figure 1 is a side view of a toilet brush showing my new design; Fig. 2 is a top view thereof; and Fig. 3 is an end view.

I claim:

The ornamental design for the toilet brush as shown.

JACOB H. SCHEUER.

In the presence of—

F. WARNECK,

M. KUHL.
